UNITED STATES PATENT OFFICE.

LAWRENCE H. DOLAN, OF ALEXANDRIA, INDIANA, ASSIGNOR OF THREE-FOURTHS TO THOMAS A. NILAN, LOUIS KAUFFELD, AND VALENTINE LIBLER, OF SAME PLACE.

DESIGN FOR A BULB FOR INCANDESCENT LAMPS.

SPECIFICATION forming part of Design No. 26,616, dated February 9, 1897.

Application filed January 4, 1897. Serial No. 617,964. Term of patent 7 years.

To all whom it may concern:

Be it known that I, LAWRENCE H. DOLAN, a citizen of the United States, residing at Alexandria, in the county of Madison and State of Indiana, have invented and produced a new and original Design for a Bulb for Incandescent Lamps, of which the following is a specification.

Reference is to be had to the accompanying drawing, forming a part of this specification, which represents in elevation a bulb embodying my new design.

The design in its entirety shows a series of facets produced on the bulb, the facets being diamond shape and defined by intersecting lines of V-shaped surfaces, the whole being

combined with a bulb polygonal in cross-section, alternate intersections of the V-shaped surfaces being coincident with the angles formed by the sides of the bulb.

The leading feature of my design consists in the bulb, having a faceted face, the facets being defined by intersecting V-shaped surfaces.

I claim—

The design for a bulb for incandescent lamps, herein shown and described.

LAWRENCE H. DOLAN.
